UNITED STATES PATENT OFFICE.

EDUARDO GOMES FERREIRA, OF RIO JANEIRO, BRAZIL.

SHUTTLE FOR WEAVERS' LOOMS.

SPECIFICATION forming part of Letters Patent No. 728,694, dated May 19, 1903.

Application filed July 26, 1902. Serial No. 117,161. (No model.)

To all whom it may concern:

Be it known that I, EDUARDO GOMES FERREIRA, manufacturer, a citizen of the Republic of Brazil, residing at 83^a Rua Primeiro de Marco, Rio Janeiro, Brazil, have invented certain new and useful Improvements in Shuttles for Weavers' Looms, of which the following is a specification.

This invention relates to certain new and useful improvements in weavers' shuttles; and the object thereof is to provide a shuttle with a device to assist in rapidly passing the bobbin-thread through the eye of the shuttle, thereby overcoming the objection to suction generally employed for this purpose.

The invention further aims to construct the said device in such a manner that it will cause the bobbin-thread after unwinding to pass in an oblique manner toward the eye of the shuttle.

The invention further aims to construct a weaver's shuttle provided with a device, as set forth, which shall be simple in construction, strong, adapted to reinforce the head of the shuttle, durable, efficient in its use, and comparatively inexpensive to manufacture.

With the above and other objects in view the invention consists of the novel combination and arrangement of parts hereinafter more specifically described, illustrated in the accompanying drawings, and particularly pointed out in the claims hereunto appended.

In describing the invention in detail reference is had to the accompanying drawings, forming a part of this specification, wherein like reference characters denote corresponding parts throughout the several views, and in which—

Figure 1 is a sectional elevation of a shuttle provided with my improved threading and thread-directing device. Fig. 2 is a plan of a shuttle with my improved device attached thereto. Fig. 3 is a side elevation of the head of the shuttle, showing my improved device in dotted lines. Fig. 4 is a section on the line *a b* of Fig. 1. Fig. 5 is a front view, Fig. 6 is a top plan view, Fig. 7 is side elevation, and Fig. 8 is a rear elevation, of the threading device; and Figs. 9 and 10 are a side and a top plan, respectively, of the socket adapted to be mounted in the eye-bore.

Referring to the drawings by reference

characters, the head of the shuttle is provided with a recess 1, having an open top *a*, and which is a continuation in a longitudinal direction of the opening *B* in the shuttle for the bobbin *C*. The bobbin *C* is mounted upon the spindle *E*. The shuttle-head is provided with an oblique bore 2, terminating at its inner end in the recess 1 and at its outer end in a shuttle-eye *D*. The bore 2 will be termed the "eye-bore."

Within the recess 1 is secured, by means of the rivets 4 or other suitable fastening means, the threading and thread-directing device *A*, which is constructed of a pair of side walls 3², the bottom wall 3', and a forward or main wall 5. The bottom wall 3 is preferably curvilinear in contour and is or may be formed integral with the side walls 3² and is further constructed in such a manner that its forward edge or end extends in an oblique manner. The side wall 3² is of a greater length than the side wall 3', and the walls 3 3' 3² are or may be formed integral with the forward or main wall 5. From the construction of the threading and thread-directing device it will be evident that the forward or main wall 5 will extend obliquely of the recess 1. The forward or main wall 5 is provided with an orifice 6, which lies in a plane with the axis of the spindle *E* of the bobbin *C*. The orifice 6 is adapted to permit of the free passage of the thread from the bobbin *C*, while the device *A* maintains the thread during its passage in the direction of the bore 2—that is, obliquely. The forward or main wall 5 of the threading device is provided with a slit *t*, which extends upwardly in an oblique manner from the orifice 6 to the corner formed by the juncture of the walls 3² 5. The slit *t* permits of the introduction of the thread *o* to the threading device *A*. The introduction of the thread *o* to the threading and directing device *A* is assisted by providing the end of the slit *t* with an enlarged mouth 9, formed by the rounding off of the wall 3² at an angle to the top edge 10 of the wall 3² toward the edge 8 and the rounding off of the wall 5, as at 11.

The lateral wall of the recess 1 on the side of the eye *D* is provided with a vertical or slightly-inclined slit 12 and which extends from the top of the wall of the recess to the bore 2.

The eye-bore 2 may be provided with a slitted eyelet or metallic socket F with fixing-lugs 13, and the slit therein is indicated at 12', corresponding to the slit 12 in the wall of the 5 recess 1.

From the foregoing it will be evident that to introduce the thread o into the orifice 6 and bore 2 the thread is grasped and passed to the orifice 6 through the slit t, the mouth 9 of the 10 slit t facilitating the passage of the thread. The thread o is then placed in the slit 12 and finally pulled downward into the eye-bore 2, with its free end outside the shuttle. It will also be evident that the threading device will 15 reinforce the head of the shuttle, owing to the fact that it is connected, by means of the rivets 4, thereto. It will also be evident that owing to the obliquely-extending wall 5 of the threading and thread - directing device the 20 thread will be directed obliquely toward the eye of the shuttle.

It is thought the many advantages of my improved shuttle can be readily understood from the foregoing construction, taken in 25 connection with the accompanying drawings, and it will also be evident that minor changes may be made in the details of construction without departing from the general spirit of my invention.

30 Having thus fully described my invention, what I claim as new, and desire to secure by Letters Patent, is—

1. In combination with a shuttle provided with an eye, of a threading and thread-directing device mounted therein and consisting of a pair of side walls, a bottom and a main wall, said main wall extending obliquely and provided with an orifice and an obliquely-extending slit terminating at its lower end in 35 said orifice.

2. A threading and thread-directing device for shuttles comprising a pair of side walls, one of which is of greater length than the other, a bottom wall connected therewith 40 and a main wall extending in an oblique

manner and connected to the said side and bottom walls, said main wall provided with an orifice, and a slit terminating at its lower end in said orifice, said slit extending in an oblique manner and provided with an enlarged mouth. 50

3. A threading and thread-directing device for shuttles comprising a pair of side walls, one of which is of greater length than the other, a bottom wall connected therewith and 55 a main wall extending in an oblique manner and connected to the said side and bottom walls, said main wall provided with an orifice and a slit terminating at its lower end in said orifice, said slit extending in an oblique 60 manner.

4. In combination, a shuttle provided with a recess and an eye-bore extending in an oblique manner, said shuttle further provided with a slit terminating in said bore, a threading and thread-directing device mounted in 70 said recess and provided with a main wall extending in the same direction as the said bore, said main wall further provided with an orifice and an obliquely-extending slit terminating in said orifice.

5. In combination, a shuttle provided with a recess and an eye-bore extending in an oblique manner, said shuttle further provided with a slit terminating in said bore, a threading and thread-directing device mounted in 75 said recess and provided with a main wall extending in the same direction as the said bore, said main wall further provided with an orifice and an obliquely-extending slit terminating in said orifice, said slit having an 80 enlarged mouth.

In testimony whereof I have hereunto set my hand in presence of two subscribing witnesses.

EDUARDO GOMES FERREIRA.
